H. LAMOTTE.

Apparatus for Rectifying Alcohol.

No. 59,149.

Patented Oct. 23, 1866.

UNITED STATES PATENT OFFICE.

HENRI LAMOTTE, OF PERCY STREET, BEDFORD SQUARE, COUNTY OF MIDDLESEX, ENGLAND.

IMPROVED APPARATUS FOR RECTIFYING ALCOHOL.

Specification forming part of Letters Patent No. 59,149, dated October 23, 1866.

To all whom it may concern:

Be it known that I, HENRI LAMOTTE, of Percy Street, Bedford Square, in the county of Middlesex, England, have invented a new or Improved Method of and Apparatus for Rectifying Alcohols; and I do hereby declare that the following is a full and exact description thereof, reference being had to the accompanying drawing, and to the letters of reference marked thereon.

The object of this invention is to cause good and fine-tasted alcohols to flow or run off continuously, because only alcohols of a high character are allowed to enter the rectifying-column, the foreign matters which had been amalgamated with the alcohol having been previously condensed in a purifier by means of cold water.

By means of this new and improved method no taste of copper is given to the alcohol, for, this taste being produced by the cooling of the apparatus, and this being always in action, it follows that the cooling cannot take place, and consequently that a copper taste is no longer produced.

To enable others skilled in the art to make and use my invention, I will proceed to describe its construction and operation.

My said invention consists in two distilling or boiling vessels, in combination with a rectifying-column and purifying-vessels, arranged and operating in such a manner that the rectifying operation can be carried on continuously, and the ethereal products separated from the alcohol at the commencement of charges introduced alternately in the boiling-vessels, and the foreign substances separated from the alcohol at the end of the operation. The boilers are coupled together or united by tubes, one of which is in communication with a purifier and refrigerator, another with the column, and another with the bottom of the column and extending down into the boilers themselves.

In the accompanying drawing, A A No. 1 and No. 2 are steam vessels or boilers. B is a rectifying-column or analyzer above the steam-boilers. C is a condenser. D is a refrigerator. E is a refrigerator for the ethereal products of those alcohols at the end of the heating.

F is a tubular purifier, which only allows the best alcohols to pass into the column. G is the tubular purifier, wherein the alcohol conveyed by the lightest fluids at the commencement of the heating is condensed, and for condensing the other foreign bodies conveyed by the alcohol at the end of the heating.

H is a pipe through which the first products from the boiler pass to the purifier G. I is the pipe leading to the column. J is a pipe descending to the vessels A, and for conveying thereto the condensed vapors proceeding from the column. K is a pipe leading to the testing apparatus; L, testing apparatus; M, tap for admitting water to the purifier G; O, tap for admitting water to the purifier F; Q, tap in the pipe I, leading to the column; R, tap in the preparation-tube H; S, tap in the descending tube J; T, tap in the tube leading to the small testing apparatus L.

The operation is as follows: Supposing boiler No. 1 is first used, the tap R is opened after the boiler is charged, and the valves Q and S are kept closed. As soon as 74° centigrade of heat are produced, the foreign matters, which are lighter than the alcohol, begin to disengage themselves. The tap M of the purifier G is then immediately opened and a slight stream of water passes through, in order to condense the alcohol which the foreign matters bring with them. As soon as the foreign matters become disengaged, the taps Q and S are opened and the taps R and M are closed.

While the boiler No. 1 is at work, boiler No. 2 may be prepared for work, the action of which is similar to the other, and it is thus ready for use as soon as the other is finished. If, however, the boiler No. 2 is ready somewhat before the other has finished operations, the tap Q of the boiler No. 2 may be slightly opened while waiting for the termination of the other. There is no possible inconvenience attending the working, for the alcohol of boiler No. 2 cannot enter that of No. 1, seeing that that which commences has only 80° to 87° centigrade of heat, while that which finishes has from 92° to 95° centigrade. Besides, when No. 1 is finished the taps Q and S are closed, and the tap R opened and the tap M of the purifier, and the rest of the alcohol from the boiler No. 1 passes through the prep-

aration-pipe I and through the purifier G, where all matters foreign to the alcohol become condensed and return in spray into the boiler.

The action of the boiler No. 1 being terminated, the tap M of the purifier G only is closed, and the same boiler is charged and discharged as before described.

The purifiers F and G are each formed with a series of vertical pipes, open at their ends, passing through a water-space formed between heads that receive said pipes through them. The temperature of these purifiers is regulated by water admitted through the cocks O or M, and running off by an overflow.

The testing apparatus L is made with a small pipe in the inside, acting as a condenser, to furnish liquid with convenience to test when the operation is complete in either boiler No. 1 or No. 2.

Thus the one vessel works to produce the good-tasted alcohol when the valves Q and S are open and the valve R closed. The reverse takes place for the other: it has its tap R open and the valves Q and S closed. The tap M will be open if the purifier G works.

By the foregoing arrangements the alcohols are very superior, much more work is accom-

plished, and fuel is economized. The produce is also greater, as it is not necessary to distill a second time all the alcohols which have a copper taste, and which are dangerous by the combinations of the oxides of copper which form during cooling.

Another advantage resulting from this system is, that more work is accomplished with it than with two apparatus of the ordinary construction.

What I claim, and desire to secure by Letters Patent, is—

The boilers A No. 1 and A No. 2 and rectifying-column or analyzer B, in combination with the purifiers F and G, the parts being connected by pipes and regulated by cocks or taps, in the manner and for the purposes set forth.

In witness whereof I, the said HENRI LAMOTTE, have hereunto set my hand and seal this 21st day of May, 1866.

LAMOTTE. [L. S.]
